UNITED STATES PATENT OFFICE.

JOHN FRANKLIN GEORGE, OF CAMDEN, NEW JERSEY, ASSIGNOR TO C. HOWARD HUNT
PEN COMPANY, OF CAMDEN, NEW JERSEY, A CORPORATION OF NEW JERSEY.

PEN-BLANK-FORMING MACHINE.

1,086,156.

Specification of Letters Patent.

Patented Feb. 3, 1914.

Application filed January 7, 1913. Serial No. 740,654.

To all whom it may concern:

Be it known that I, JOHN FRANKLIN GEORGE, a citizen of the United States, residing in Camden, Camden county, New Jersey, have invented certain Improvements in Pen-Blank-Forming Machines, of which the following is a specification.

One object of my invention is to provide a relatively simple, rapidly operating and accurate machine for marking and forming the previously cut flat blanks from which pens are to be made; it being also desired that the machine shall be relatively efficient and have its parts so arranged that they are not likely to get out of order or require repair.

Another object of the invention is to provide a machine of the above noted type with novel devices for preventing it from being started unless the pen blank-carrying members occupy the proper positions relatively to the punch carrying member or members.

The invention also contemplates novel means for actuating and locking the blank carrying member of the machine and likewise a novel arrangement of parts for placing and thereafter holding a pen blank prior to and during its marking, as well as novel means for specifically forming and discharging the finished pen blanks.

These objects and other advantageous ends I secure as hereinafter set forth, reference being had to the accompanying drawings, in which,

Figure 1 is a front elevation of a pen making machine constructed according to my invention; Fig. 2 is a plan, partly in section and on an enlarged scale, further illustrating the machine; Fig. 3 is a fragmentary plan of a part of the rotary plate on a larger scale than Fig. 2, showing the presser foot in its operative position; Figs. 4 and 5 are vertical sections on the lines *a—a* and *b—b* Fig. 3. Figs. 6 and 7 are full-sized vertical sections taken in planes at right angles to each other on the lines *c—c* and *d—d*, Fig. 2, and illustrating the operation of the marking apparatus forming part of my invention; Fig. 8 is a plan of the marking die; Figs. 9 and 10 are full-sized vertical sections taken at right angles to each other on the lines *e—e* and *f—f*, Fig. 2, and illustrating the operation and detailed construction of the blank shaping members with

their associated parts; and, Fig. 11 is a plan of the blank discharging device.

In the above drawings 1 represents the base or foundation of the machine on which is mounted a yoke or framework 2 providing bearings for a horizontal main shaft 60 (not shown) on which is fixed a driving pulley 3 and a pair of cranks operating connecting rods 4 and 5. Through suitable gearing forming no part of the present invention, power is transmitted from the main shaft to a vertical shaft 7 which is carried in a bearing 8 supported at one side of the frame 2, and having fixed to it a crank 9 and cam 10.

The crank 9 is connected through a rod 70 11 with an oscillatory arm 12, journaled on a vertical spindle 13, mounted in a suitable manner at substantially the center of a stationary circular plate or disk 14, carried by the base 1. The arm 12 has attached to it 75 a pawl 15 shown in dotted lines in Fig. 2 and normally drawn by a spring 17 toward a ratchet plate 16 which is fixed to or formed as part of a rotary plate 18 mounted on the spindle 13 so as to be substantially concentric with the stationary plate 14. The rotary plate 14 has mounted on it a number of sets of blank holding members hereinafter described in detail, there being in the present instance eight sets of said members 85 spaced equidistant upon said plate, and for locking the latter in any one of its eight operative positions, it is provided with a number of peripheral locking recesses 19, designed to coöperate with a locking bolt 20 90 forming part of or mounted on a slide 21 which is reciprocable in suitable guide ways at one side of the main frame. This slide is actuated by a horizontally placed member 22 having an elongated slot for the reception 95 of the vertical shaft 7 and carrying a roller 23 placed to be engaged by the cam 10 on said shaft. The locking bolt 20 with its slide 21, member 22 and the roller 23 is at all times drawn toward the rotary plate 18 100 by a spring 24 acting between a pin 25 on said member 22 and a projection 26 on the frame of the machine.

For controlling the operation of the machine I provide a pin controlled or other 105 suitable clutch 27 of the form common in punches and like machines, and connect its governing pin 28 through a link 29 with a

hand lever 30, mounted in the present instance at that side of the frame 2 opposite the locking bolt 20.

In order to prevent the starting of the machine when the rotary plate 18 with its associated parts is in other positions than those in which the locking bolt 20 is in engagement with a recess 19, I provide a slideable bar 31 mounted in the framework 2 in such position as to be capable of engaging or entering the teeth of the ratchet wheel 16 toward which it is at all times pressed by a spring 32. Said bar is so proportioned that when its inner end is fully entered in one of the teeth of this ratchet wheel, its outer end just clears the starting lever 30 so as to allow this to be moved downwardly in order to start the machine; and when said bar is so engaged the locking bolt 20 is entered in one of the recesses 19 thus rigidly holding the rotary plate 18. At any other time, the bar 31 is necessarily held outwardly by a tooth of the ratchet wheel 16 against the action of the spring 32, so that the starting lever cannot be moved downwardly because the end of said bar is projected immediately beneath said lever. Attached to the connecting rods 4 and 5 which each form part of a toggle, are two other members 33 and 34 to whose lower ends are connected heads 35 and 36 free to slide vertically in guide ways 37 on the frame 2. The head 35 has fixed to its lower end a presser foot 38 and a punch 59, while the head 36 has fixed to its lower end a punch 60.

The presser foot shown in dotted lines in Fig. 3 and in Figs. 4 and 5, consists of a substantially vertical member whose lower end 39 is extended horizontally so that its front portion has parallel sides while its rear portion is undercut as indicated at 39^a in Fig. 5 for a purpose hereafter noted.

At points mid-way between the locking recesses 19 (Fig. 3), the periphery of the rotary plate 18 is provided with a relatively deep parallel sided recess, on each side of which are two relatively elongated slots 40 and 41 in the first or outer pair of which are mounted slides 43 carrying bolts 42 whose heads enter undercut portions of the rotary plate 18 which extend parallel with the slots 40 so that said slides may be moved toward and from the periphery of said plate. On each of the slides is mounted a blank engaging finger 44 provided with a longitudinal slot 45 extending in a direction substantially at right angles to the line of the slot 40. The slides 43 may be clamped in any adjusted position by the nuts on the bolts 42, and there are relatively large washers 46 interposed between said nuts and the adjacent upper end of each slide, the arrangement being such that the fingers of each pair are movable on their slides 43 toward and from each other. At all times said fingers are

forced toward each other by springs 47 engaging their rear ends and mounted on the bolts 42. As shown in Fig. 4, the fingers 44 while having their body portions mounted on the upper face of the rotary plate 18, have their pen engaging ends extended downwardly so that their lower or under surfaces engage with or lie immediately adjacent to the top face of the stationary plate 14. Moreover, as shown in Fig. 4, the adjacent ends of these fingers are not only upwardly and backwardly inclined from said stationary plate but immediately adjacent thereto, are nicked or recessed at their extremities so as to be capable of receiving and holding the flat pen blank X. The flat portion 39 of the presser foot 38 has mounted in it a vertically movable pin 48 serving as an auxiliary or holding device which is at all times pressed downwardly by a suitably formed spring 49 attached to the main presser foot in any desired or suitable manner.

Lying substantially parallel with the fingers 44 is a second set of fingers 50 which likewise are carried on the upper face of the rotary plate 18 and are longitudinally slotted as indicated at 51, for the reception of a slide 52 which in turn extends into the slot 41 of said rotary plate. Bolts 53 serve to connect the plate with the respective slides and their fingers, although in this case said bolts rigidly clamp the parts to said plate so that after being adjusted, they are immovably held in place, the bolts as before having head portions in the enlarged lower portions of the slots 41. The adjacent ends of the fingers 50 are downwardly extended so that their under portions rest upon or are immediately adjacent the top surface of the stationary plate 14, and like fingers 44, have nicks or recesses for the reception of the rear end of a pen blank X, so that this will be held in engagement with the said fixed plate. It is noted that the fingers 44 are preferably so spaced apart by means of set screws 55 placed in their outer ends to engage the slides 43, that the distance between them is normally less than the width of the presser foot, which on being lowered, forces them apart against the action of the springs 47. The upper adjacent edges or end portions of the fingers 50 are outwardly inclined or flared as shown in Fig. 5, though to a less extent than the fingers 44.

As shown in Fig. 1, the slideable head 35 of the press, in addition to the presser foot 38 carries a punch 59 so mounted that when said head descends it will engage a pen blank held by one set of fingers 44-50 at the same time that the presser foot engages and places the pen blank held by a preceding set of fingers, it being noted that under operating conditions the rotary plate turns in the direction of the arrow indicated in Fig. 2. As

best shown in Figs. 6 and 7 the punch 59 is rigidly held in the head 35 by a set screw 55.

Immediately under the stationary plate 14 in the vertical line of movement of this punch 59 there is mounted a die supporting block 56 held to the base structure 1 by a dowel 57 which enters a suitably formed recess; there being a pin 58 extending transversely through the block 56 and the dowel so as to properly hold these parts together. The upper face of the die block is recessed for the reception of a marking die 61, which in this case is in the form of an elongated relatively narrow block having an upwardly projecting portion 62 whose top face has formed in it the letters or symbols, etc. which it is desired to impress on the pen blank. A plate 63 surrounds this upwardly projecting portion 62 of the die, which with said plate, has its top surface substantially flush with or slightly below the top face of the stationary plate 14, and said plate 63 is held to the die by screws 64 as shown in Fig. 7. Set-screws 65 serve to rigidly hold the die 61 to the block 56.

As indicated in dotted lines in Fig. 2 the stationary plate 14 is cut away to a suitable extent under the sliding punch head 36 and in this space is mounted a second die block 66 supported on the base 1, and positioned by a pin or dowel 67 to which it is locked by a transverse pin 68. The top face of this block is recessed for the reception of a die 69 which may be rigidly held in place by a wedge 70 and in turn is locked in position by a set screw 71. Upon those parts of the block 66 on opposite sides of said die are two sets of relatively flat positioning fingers 66^a and 66^b projecting over the die so as to guide a flat pen blank as it is forced down out of the fingers 44-50. Each of these positioning fingers is longitudinally slotted for the reception of an adjusting screw 66^c whereby it may be rigidly held in a given position. The punch head 36 in this case carries a punch 60 in the shape of a narrow elongated plate whose lower end is made convex and is otherwise so formed as to match with the recess in the upper face of the die 69 in order to properly shape a pen blank to give it the well known upwardly convex form. This punch is held to the lower end of the sliding head 36 by a set-screw 73 which head also carries a pin or plunger 74 having a head 75 slidable in a cavity of the sliding head and normally pressed downwardly by a spring 76. The part of this plunger projecting outside of the head structure carries a stripper plate 77 designed to wipe one side of the punch 60 adjacent the lower end thereof.

As shown in Fig. 10, the die 69 does not entirely fill the recess provided for it in the top of the die block 66 so that there is a cavity into which projects a discharging finger

78, movable on a vertical pivot 79 in a recess in the die block 66 and pivotally connected by a screw 80 to a slidable plate 81. This latter is provided with two slots, as shown in dotted lines in Fig. 10, for the reception of a pair of screws 82 and is at all times pressed outwardly by a spring 83, one end of which is connected to it while the other is attached to the die block so that the outer end of said plate engages and co-acts with the toothed plate or ratchet 16. This discharging finger 78 is mounted in position to engage the rear of a finished pen blank so as to move it radially away from the central pivot 13 and there is provided a chute 85 for the reception of the blank when so discharged.

With the above described arrangement of parts, power from a suitable source is applied to the pulley or fly wheel 3 which turns idly on its shaft unless the lever 30 be so thrown as to operate the clutch 27 through the link 29 and pin 28. Obviously, however, such operation of the lever cannot occur unless the locking bar 31 under the action of the spring 32, is projected inwardly toward the vertical spindle 13 to its maximum extent, under which conditions its inner end fits into the lowest part of any one of the teeth of the ratchet plate 16. Under these conditions the rotary plate 18 is in such position that one set of its fingers 44-50 is in such position that the presser foot 38 can force its way between them, while at the same time the next succeeding set of fingers is properly placed to permit of the punch 59 engaging the pen blank held by them. At the same time, still another set of fingers lies immediately under the slidable punch head 36 so that the punch 60 may properly engage a pen blank held by them, and it may be noted that this latter blank necessarily lies at the point immediately adjacent the open end of the chute 85.

Immediately after the clutch 27 is thrown into action, the crank operating the connecting rod 4 so actuates this and the toggle member 33 that the sliding head 35 is moved downwardly for a working stroke. The two cranks are so set that after the head 35 has moved down and started on an up stroke, the head 36, which acts behind it, completes its downward working stroke and also starts up. The revolution of the main shaft, through the gearing in the casting 6, likewise turns the shaft 7, and the parts are so arranged and set that after the head 36 has moved up far enough to permit its punch 60 to clear the fingers 44-50 and their associated parts, the cam 10 acts on the roller 23 to move the part 22 with the slide 21 and the locking tooth 20, away from the rotary plate 18, thus releasing this latter. Immediately thereafter, the rotation of the crank disk 9 by the shaft 7 causes the

arm 12 to be swung on its pivot through the rod 11, thus moving forward the pawl 15 and carrying with it the ratchet plate 16 together with the rotary plate 18 and their associated parts. In Fig. 2 said plates and cranks are shown in the positions occupied after the arm with the ratchet plate has been moved forwardly to a distance which is equal to the distance between the two sets 5 of fingers 44-50 and just prior to the swinging back of said arm with its pawl preparatory to another stroke. Immediately after the rotary plate 18 has been brought to rest, the roller 23 falls off of the 10 high part of the cam 10 and by the action of the spring 24 the locking tooth 20 is entered in that one of the notches 19 of said rotary plate which lies immediately adjacent it so that the plate is rigidly held from 15 movement until it is again released by the withdrawal of this locking tooth.

From the above description it will be seen that the rotary plate 18 with its various fingers is turned through an angle equal 20 to the angular distance between two sets of fingers 44-50 and after each movement is firmly locked in place. While so held the two punch heads with their punches make their working or downward strokes, 25 after which the rotary plate is again unlocked and moved forward for a predetermined distance. With the machine so actuated the operator places a flat pen blank which has previously been punched or died 30 out of a strip of suitable material, between the two fingers 44 of one of the sets at the front of the machine and pushes it rearwardly or toward the central spindle 13 until its rear end is engaged and stopped by 35 the fingers 50. Thereafter the intermittent movement of the plate 18 carries this set of fingers with the blank until it passes under the presser foot 38, which when the head 35 makes its next working stroke, forces 40 apart the fingers 44 and presses the flat blank down upon the upper face of the stationary plate 14 so that said fingers 44 are free to come together for a limited distance until the blank is entered in their notches 45 or recesses, this action occurring as the part 39 of said presser foot is raised and while the blank is held down by the spring pressed pin 48 which extends below the lower face of the presser foot. The blank is thus 50 firmly held by the two sets of fingers 44 and 50, so that it lies in contact with or immediately adjacent the top face of the stationary plate 14, and at the next movement of the rotary plate 18 is carried under 55 the punch 59 into the position shown in Figs. 6 and 7. When said punch next descends, it engages the pen blank and with the co-action of the die 61, impresses thereon the manufacturer's name or any other 60 desired matter. On the next movement of

the plate 18, the pen blank is carried into a position immediately over the die 69, although it is held by the fingers 44-50 slightly above the same, and upon the descent of the punch 60, it is forced out of 70 said fingers between the positioning fingers 66^a and 66^b, and into the cavity of the die 69, in which it is given the desired shape. Upon the upward movement of the head 36, the finished blank is removed from the 75 punch 60 by the stripper plate 77, which under the action of the spring 76, remains stationary relatively to said punch which it engages. Immediately thereafter, the rotary movement of the ratchet plate 16 removes the high part of one of the teeth thereof from under the plate 81 and as a consequence, this latter under the action of the spring 83, suddenly moves inwardly, 80 causing the projecting end of the discharging finger 78 to violently strike the rear end of the finished blank and force it into the chute 85.

It will be understood that each time the movement of the plate 18 ceases, a pen blank is put into position between a set of the fingers 44-50 which is temporarily at the front of the machine, so that three blanks are operated on by the presser foot and the two punches whenever the heads 35 and 36 make a working stroke. At any time the machine may be stopped by an upward movement of the lever 30 and the rotary plate may thereafter be turned forward by hand so as to adjust any of the 95 parts, or for any other purposes, though it is necessary in each instance that said plate shall be locked in one of its predetermined positions with the tooth 20 in one of its recesses 19 before the slideable bar 31 can move 100 under the action of the spring 32 into such position as to allow operation of the lever 30 with the consequent starting of the machine.

The positioning guiding fingers 66^a and 66^b perform a very necessary function in insuring the proper entry of a pen blank into the die even though the fingers on the rotary plate may hold it slightly to one side or the other instead of directly above, said 110 die. Moreover, these fixed guiding fingers which it will be noted have their adjacent portions beveled, prevent the tilting of the pen blank prior to its entrance into the die so that the blanks are without exception so 115 forced into the die that they are acted upon 120 and shaped in the desired manner.

I claim—

1. The combination, in a pen-blank forming machine, of a reciprocating punch; a 125 die; a rotatable plate; a plurality of sets of blank-holding fingers mounted on the plate and means for rotating the plate to bring the blanks carried by the sets of fingers successively between the punch and the die; 130

- with a device for successively discharging the blanks in a direction radial of said plate after they have been acted on by the punch and die.
- 5 2. The combination, in a pen-blank forming machine, of a marking punch; a die therefor; a forming punch; a die for said latter punch; means for actuating the punches; a rotatable plate; a plurality of 10 sets of pen-blank holding fingers mounted on the plate; and means for intermittently moving the plate to bring the blanks carried by said sets of fingers successively between the punches and their respective dies.
- 15 3. The combination, in a pen-blank forming machine, of a reciprocating punch; a die; a rotatable plate; a plurality of sets of pen-blank holding fingers mounted on the plate; certain of the fingers of each set being 20 movable, and the others being fixed; with means for rotating the plate to bring the blanks carried by the fingers successively between the punch and the die.
4. The combination, in a pen-blank forming machine, of a reciprocating punch; a die; a member movable in a plane substantially at right angles to the line of movement of the punch; blank holding means on said member consisting of a pair of fingers 25 movable toward and from each other; and blank limiting means consisting of a second pair of relatively fixed fingers; with means for moving said member between the punch and the die.
- 30 5. The combination, in a pen-blank forming machine, of a reciprocating punch; a die; a stationary plate; a second plate movable adjacent thereto; blank holding fingers mounted on said second plate and having 35 means for carrying a blank immediately adjacent the stationary plate; with means for moving the second plate over the first plate to bring a blank carried by said first means between the punch and the die.
- 40 6. The combination, in a pen-blank forming machine, of a reciprocating punch; a die; a stationary plate; a plate movable over said stationary plate between the punch and die; two fingers guided on the movable 45 plate so as to be adjustable toward and from each other; with a device for causing a pen blank to be gripped by said fingers; and a device for automatically discharging the blank after it has been acted on by the punch and die.
- 55 7. The combination in a pen-blank forming machine, of a reciprocating punch; a die; a rotatable plate; a fixed plate adjacent the same; a plurality of blank holding 60 fingers mounted on the rotary plate; means for causing a blank to be engaged by the fingers; and means for turning the plate to cause a blank to be brought between the punch and the die after having been engaged 65 by the fingers.
8. The combination, in a pen-blank forming machine, of a reciprocating punch; a die; a fixed supporting structure; a plate rotatable adjacent thereto and provided with substantially radial slots; a set of fingers 70 projecting into each slot and formed to hold a pen blank immediately adjacent the stationary plate; with means for intermittently moving the rotary plate to bring the blanks held by the different sets of fingers successively between the punch and the die.
- 75 9. The combination, in a pen-blank forming machine, of pen carrying means, including a movable member; a plurality of sets of fingers mounted on said member, of which 80 certain are fixed and the others are movable; with means for marking and subsequently forming a blank carried by said fingers.
10. The combination, in a pen-blank forming machine, of a radially slotted plate; a 85 supporting structure under said plate; two sets of longitudinally slotted fingers projecting into each of the slots of said plate; means for intermittently rotating the plate; means for mechanically placing a blank in 90 the grip of the fingers of each set; and means for thereafter forming said blank.
11. The combination, in a pen-blank forming machine, of a rotary plate; a plurality of sets of blank-holding fingers mounted 95 thereon; a die; a plurality of reciprocating heads; a presser foot carried by one of said heads for causing a blank to be gripped by the fingers of each set; a punch carried by the other head for co-acting with the die to 100 form a blank; and means for rotating the plate to cause the blanks to be successively presented to the presser foot and to the punch.
12. The combination, in a pen-blank forming machine, of a rotary plate; a plurality of sets of fingers mounted thereon; two dies; two reciprocating punch heads carrying punches co-operating with said dies; a presser foot also carried by one of the punch 105 heads in position to cause a blank to be gripped by a set of fingers; and means for intermittently turning the plate to cause the sets of fingers with their blanks to be successively presented to the presser foot and to 110 the two sets of punches and dies.
13. The combination, in a pen blank forming machine, of a reciprocating punch; a die; a rotatable plate; a set of pen blank holding fingers mounted on the plate; means 115 for rotating the plate to bring the fingers between the punch and the die; and a device for automatically discharging the blank after it has been acted on by the die and punch.
14. The combination, in a pen blank forming machine, of a rotatable plate; a plurality of sets of pen blank holding fingers mounted thereon; a die mounted under the plate; means for intermittently rotat- 120 125 130

- 6
- ing the plate to bring the blanks carried by the fingers successively over the die; and a punch operative to force each blank out of the fingers into the die.
- 5 15. The combination, in a pen blank forming machine, of a rotatable plate; a plurality of sets of pen blank holding fingers mounted thereon; a die mounted under the plate; means for intermittently rotating the plate to bring the blanks carried by the fingers successively over the die; a punch operative to force each blank out of the fingers into the die; with a device for automatically discharging the blanks from the die.
- 10 16. The combination, in a pen blank forming machine, of a rotatable plate; a plurality of sets of pen blank holding fingers thereon; a die mounted under the plate; means for intermittently rotating the plate to bring the blanks carried by the fingers successively over the die; a punch operative to force each blank out of the fingers into the die; with a device for automatically discharging the blanks from the die; the same consisting of a pivotally mounted finger placed to engage one end of the blank; and means for periodically actuating said finger.
- 15 17. The combination, in a pen blank forming machine, of a reciprocating punch; a die; a rotary plate; means for intermittently rotating said plate including a ratchet; means including a pawl for intermittently turning said ratchet with the plate; a plurality of sets of pen blank holding fingers carried by the plate; a die; a reciprocating punch; means for actuating the punch to force a blank from between the fingers of a set into the die; with means for discharging the blank from the die consisting of a pivotally mounted finger and a bar connected to said finger and governed by said ratchet.
- 20 18. The combination, in a pen forming machine, of a reciprocating punch; a die; a rotatable plate; a plurality of sets of pen blank holding fingers mounted on the plate; means for rotating the plate to bring the blanks carried by the sets of fingers successively between the punch and the die; driving means for said machine; and a device for preventing transmission of power from the driving means to the punch except when the sets of fingers occupy predetermined positions relatively to the die.
- 25 19. The combination, in a pen blank forming machine, of a punch; a die; blank carrying means including a rotary member; means for locking said member with the blank carrying means in a predetermined position relatively to the punch and die; driving means for the punch; means for connecting the driving means with the punch; and a device for preventing actua-
- tion of the connecting means unless the plate is locked with the blank carrying means in a predetermined position.
- 20 20. The combination, in a pen blank forming machine, of a punch; a die; a rotary plate; means for intermittently turning said plate including a ratchet; a plurality of sets of blank holding fingers carried by the plate; means for locking the plate with one set of fingers in position to present a blank to the die; a source of power; means for causing connection of the punch to said source of power; and a device controlled by the ratchet, for preventing the actuation of said connecting means except when the plate is locked.
- 25 21. The combination, in a pen blank forming machine, of a rotary plate; means for intermittently turning the plate, including a ratchet; two rotary members; a clutch for connecting said members; a die; a punch driven by one of the shafts; pen blank carrying means on the plate; and means for preventing operation of the clutch except when the blank carrying means is in position to present a blank to the die, the same consisting of a bar actuated by the ratchet; and a member for throwing the clutch, mounted to be prevented from movement by said bar except when the ratchet permits the latter to occupy a predetermined position.
- 30 22. The combination, in a pen blank forming machine, of a punch; a die; a rotary plate; a plurality of sets of blank holding fingers on said plate, of which certain are movable toward and from each other and are upwardly inclined; means co-acting with the inclined portions of the fingers for placing a pen; and means for intermittently rotating the plate to bring blanks carried by the fingers successively between the punch and the die.
- 35 23. Blank holding means for a pen forming machine, consisting of a fixed and a movable structure; with a pair of fingers mounted upon the movable structure and extending immediately adjacent the surface of the fixed structure; there being recesses in the ends of said fingers placed to hold a pen blank immediately adjacent said surface of the fixed structure.
- 40 24. Blank holding means for a pen forming machine, consisting of a fixed and a movable structure; two sets of fingers mounted upon the movable structure and extending immediately adjacent the surface of the fixed structure; the fingers of one set being yieldingly pressed toward each other, and there being recesses in the ends of the fingers placed to hold a blank immediately adjacent the surface of the fixed structure.
- 45 25. The combination in a pen-blank forming machine, of a movable plate; a plurality of sets of pen blank holding fingers mount-
- 70 75 80 85 90 95 100 105 110 115 120 125 130

ed thereon; a die mounted under the plate; fixed guiding fingers mounted adjacent the die; means for intermittently moving the plate to bring the blanks carried by the fingers thereof successively over the die; and a punch operative to force each blank out of the fingers of the plate through the fixed fingers into the die.

26. The combination in a pen-blank forming machine, of a movable plate; pen blank holding fingers mounted thereon; a die mounted under the plate; blank guiding means mounted adjacent the die; means for moving the plate to bring a blank carried by the fingers thereof over the die; and a punch operative to force the blank out of the fingers of the plate through the guiding means into the die.

27. The combination in a pen-blank form-

ing machine, of a rotatable plate; a plurality of sets of pen-blank holding fingers mounted thereon; a die mounted under the plate; a set of upwardly beveled relatively fixed guiding fingers also mounted under the plate above the die; means for intermittently rotating the plate to bring the blanks carried by its fingers successively over the die; and a punch operative to force each blank out of the plate fingers through the fixed fingers into the die.

In testimony whereof, I have signed my name to this specification, in the presence of two subscribing witnesses.

JOHN FRANKLIN GEORGE.

Witnesses:

HENRY H. MARTER, Jr.,
L. R. KIRBY.
